UNITED STATES PATENT OFFICE.

CHARLES EDGAR NORTHROP, OF DAYTON, OHIO.

CARBURETER-LOCK.

1,384,674.

Specification of Letters Patent. Patented July 12, 1921.

Application filed September 19, 1919. Serial No. 324,968.

To all whom it may concern:

Be it known that I, CHARLES EDGAR NORTHROP, a citizen of the United States, and a resident of Dayton, in the county of Montgomery and State of Ohio, have invented a new and Improved Carbureter-Lock, of which the following is a full, clear, and exact description.

The invention relates to carbureters of internal combustion engines such as are used on automobiles and other vehicles.

The object of the invention is to provide a new and improved lock more especially designed to cut off the supply of gasoline or other liquid fuel from the needle valve thereby preventing running of the engine by unauthorized persons.

Another object is to permit of conveniently applying the lock to carbureters as now generally constructed.

With these and other objects in view, the invention consists of certain novel features of construction, as hereinafter shown and described and then specifically pointed out in the claims.

A practical embodiment of the invention is represented in the accompanying drawings forming a part of this specification, in which similar characters of reference indicate corresponding parts in all the views.

Figure 1 is a side elevation of the improved locking device as applied to a carbureter, the reservoir and front of which are shown in section;

Fig. 2 is a front elevation of the same with parts in section;

Fig. 3 is an enlarged cross section of the same on the lines 3-3 of Figs. 2 and 4;

Fig. 4 is an enlarged sectional plan view of the same on the line 4-4 of Fig. 2;

Fig. 5 is a similar view of the same with the parts in a different position;

Fig. 6 is a similar view of the same with the parts in still another position;

Fig. 7 is a cross section of the same on the line 7-7 of Fig. 5; and

Fig. 8 is a cross section of the closing valve in open position on the valve seat tube of the needle valve controlling the flow of the liquid fuel from the reservoir of the carbureter to the mixing tube leading to the inlet manifold, the section being on the line 8-8 of Fig. 2.

The carbureter on which the improved lock is applied is of usual construction and is provided with a reservoir 10 containing a

float 11 controlling the usual inlet valve 12 for filling the reservoir 10 with gasoline or other liquid fuel. Through the reservoir 10 extends the mixing tube 13 for conducting the explosive mixture of gasoline and air to the inlet manifold, the said mixing tube 13 being connected at its outer end with the atmosphere in the usual manner. A needle valve 15 extends into the mixing tube 13 and controls a seat 16 on one end of a seat tube 17 provided at its other end with a valve seat 18 opening into the reservoir 10 to allow gasoline or other liquid fuel to flow from the reservoir 10 through the tube 17 into the mixing tube 13 whenever the needle valve 15 is in open position.

The valve seat 18 of the seat tube 17 is adapted to be closed by a lock-controlled shut-off valve 20 to prevent the flow of gasoline or other liquid fuel from the reservoir 10 to the mixing tube 13 even should the needle valve 15 be in open position. The shut-off valve 20 is mounted to slide in an extension 21 of the tube 17 and this valve is pressed on by a spring 22 to normally hold the shut-off valve 20 in open position. The stem 23 of the valve 20 is engaged by one end of a lever 25 fulcrumed at 26 on one side of the tube 13 and this lever is pivotally connected with an arm 27 of a bolt 28 slidably engaging the inner end of a key tube 30 mounted to turn in a suitable bearing 31 arranged on the under side of the top 32 of the reservoir 10, as plainly shown in Figs. 3 and 7. The key tube 30 extends through the top 32 into a boss 33 formed on the top 32 and normally closed by a suitable cap 34, as shown in Figs. 1 and 2. A key 40 is adapted to be inserted in the key tube 30 at the time the cap 34 is removed from the boss 33, and this key 40 is provided with a slot 41 in which is mounted to swing an arc-shaped tumbler 42 pivoted at 43 on the key 40 within the slot 41, as plainly shown in Figs. 3 and 7.

The key tube 30 is provided at its upper end on one side with a slot 44 to accommodate the tumbler 42 when inserting the key 40, and the bottom of this slot provides a cam 45 for imparting a swinging motion to the tumbler 42 to project the latter through a slot 46 formed in the opposite side of the key tube 30. The top 32 is provided with a groove 47 adapted to register with the slot 44 to allow of inserting the key with the back of the tumbler 42 passing down the registering slots 44 and 47.

The free end of the tumbler 42 is adapted to pass into a slot 50 formed radially in a tumbler plate 51 having a hub 52 mounted to turn loosely on the key tube 30. A spring pawl 55 is attached to the under side of the top 32 and normally projects into the slot 50 to hold the tumbler plate 51 against accidental turning but to allow the tumbler 42 to turn the plate on inserting the key 40 into the tube 30. A second tumbler plate 60 is mounted to turn loosely on the key tube 30 and this tumbler plate 60 is provided with a slot 61 adapted to be engaged by the tumbler 42 whenever the tumbler plate 51 has been turned until its slot 50 is in register with the slot 61, as plainly shown in Figs. 5 and 7. It is understood that normally the slots 50 and 61 are out of register with each other, as shown in Figs. 4 and 6. A spring-pressed pawl 65 is pivoted on the under side of the top 32 and is provided with two lugs 66 and 67, of which the lug 66 is adapted to be engaged by the tumbler 42 to swing the pawl 65 outward into the position shown in Fig. 5, and the other lug 67 is adapted to engage a notch 68 formed in the peripheral face of the plate 60 to hold the latter in locking position, as indicated in Fig. 6. The tumbler plate 60 is adapted to pass over the top of an arm 70 forming an extension of the bolt 28 and slidably engaging a tube 71 attached to the bearings 31. The tumbler plate 60 engages the top of the arm 70 at the time the valve 20 is pushed into closed position to hold the valve 20 locked in the closed position on the operator withdrawing the key 40 from the tube 30.

The operation is as follows:

Normally the valve 20 is in open position with the tumbler plates 51 and 60 in the position shown in Figs. 3 and 4, that is, with the slot 50 of the plate 51 in diametrical alignment with the registering slots 44 and 47. When the operator of an automobile or other vehicle desires to close the seat tube 17 by the valve 20 then the operator first removes the cap 34, then inserts the key 40 into the key tube 30 with the tumbler 42 sliding down in the registering slots 44 and 47. Prior to the lower end of the key 40 reaching the top of the bolt 28, the tumbler 42 engages the cam 45 and is thus swung through the slot 46 into engagement with the slot 50 in the tumbler plate 51. The operator now turns the key 40 thereby turning the tumbler plate 51 to the position shown in Fig. 5, that is, until the slot 50 registers with the slot 61. The key 40 is now pressed further downward in the tube 30 to cause the bolt 28 to move downward and impart a swinging motion to the lever 25 which, acting against the stem 23 of the valve 20, moves the latter into closed position on the seat 18 of the tube 17. The operator now

gives a further turn to the key 40 whereby the tumbler plates 51 and 60 are swung into the position shown in Figs. 5 and 7 thus moving the tumbler plate 60 over the top of the branch arm 70 moved downward with the bolt 28 below the under side of the tumbler plate 60. When the tumbler plate 60 reaches this final position the lug 67 of the pawl 65 engages the notch 68 in the tumbler plate 60 thus locking the latter against return movement. The operator now slightly withdraws the key to disengage the tumbler 42 from the slot 61 but to remain in the slot 50 thus allowing of giving a return turning movement to the key to turn the tumbler plate 51 back into its normal position, shown in Figs. 3, 4 and 6, that is, with the slot 50 diametrically opposite the registering slots 44 and 47. The key 40 can now be withdrawn from the tube 30 but as the tumbler plate 60 extends over the branch arm 70 of the bolt 28 the latter is held against return movement and consequently the valve 20 is held in closed position on its valve seat 18. By this arrangement gasoline or other liquid fuel cannot now flow from the reservoir 10 into the mixing tube 13 and consequently the formation of an explosive mixture is prevented and the engine cannot be run even should the needle valve 15 be opened. When it is desired to allow the valve 20 to move into open position by the action of its spring 22 then the operator reinserts the key 40 in the tube 30 whereby the tumbler 42 reengages the slot 50 to allow of turning the tumbler plate 51 back until the slot 50 registers with the slot 61. On pushing the key downward the tumbler 42 engages the lug 66 thus swinging the pawl 65 outward to disengage the lug 67 from the notch 68 thus unlocking the tumbler plate 60. On now turning the key 40 in reverse direction, the tumbler plates 51 and 60 are turned simultaneously in a reverse direction until the tumbler plate 60 clears the branch pin 70 and the tumbler engages the lug 66 whereby the latter is pushed downward out of engagement with the slot 61. A further turning of the key imparts a further turning movement to the tumbler plate 51 to move the slot 50 out of register with the slot 51 and into diametrical alignment with the slots 44 and 47 to permit of withdrawing the key from the tube 30. It is understood that when the tumbler plate 60 moves out of engagement with the arm 70, the valve 20 can move to its seat 18 on the withdrawal of the key 40 from the tube 30.

Some of the features of the lock are similar to corresponding ones in the lock shown and described in the Letters Patent of the United States, No. 1,274,313, granted to me July 30, 1918.

Having thus described my invention, I

claim as new and desire to secure by Letters Patent:—

1. A carbureter lock, comprising a closing member that is adapted to be mounted on the valve seat tube of the needle valve of a carbureter to close the said valve seat tube, an actuating element that is adapted to actuate the said closing element, and a key controlled means for operating the said actuating member and locking it in position. 5
2. A carbureter lock, comprising a closing member that is adapted to be mounted on the valve seat tube of the needle valve of a carbureter to close the said valve seat tube, an actuating element that is adapted to actuate the said closing element, and a key controlled means for operating the said actuating member to move the closing element into closed or open position, the said key controlled means locking the said actuating member in either position. 15
3. In a carbureter lock, a shut-off valve arranged in the reservoir of the carbureter and adapted to close the valve seat tube of the needle valve, a lever controlling the said shut-off valve, a lock arranged within the said reservoir and provided with a bolt adapted to actuate the said lever, and a key controlled means mounted in the said reservoir and controlling the said bolt, the said key controlled means having a key tube extending to the outside of the reservoir for insertion of a key. 25
4. In a carbureter lock, a shut-off valve arranged in the reservoir of the carbureter and adapted to close the valve seat tube of the needle valve, a lever controlling the said shut-off valve, a lock arranged within the said reservoir and provided with a bolt adapted to actuate the said lever, a key controlled means mounted in the said reservoir and controlling the said bolt, the said key 30
- controlled means having a key tube extending to the outside of the reservoir for insertion of a key, the said key tube having a side slot and being mounted to turn, and a key having a pivotally mounted tumbler adapted to pass through the said slot to actuate the said key controlled means, the said key being adapted to engage the said bolt to actuate the latter. 45
5. A carbureter lock comprising the combination with the needle valve of a carbureter, of a closing member adapted to be mounted on the valve seat tube of said needle valve, an actuating element adapted to actuate the closing element, and a key controlled means for operating said actuating member and locking it in position. 50
6. In a carbureter lock, the combination with the valve seat tube of the needle valve of the carbureter; of a closing member mounted on and coöperating with said valve seat tube, an actuating element for said closing element, and a key controlled means for operating said actuating member to move the closing element into closed or open position, said key controlled means locking said actuating member in either position. 60
7. In a carbureter lock, the combination with the valve seat tube of the needle valve of a carbureter and a valve coöperating therewith at one end to control the flow of gasoline from the reservoir of the carbureter; of a closing member coöperating with the other end of the tube and adapted to close or open the supply of the liquid fuel to the carbureter independent of the needle valve thereof, a controlling means controlling said closing member, and means for operating said controlling means and locking and holding it in position. 75
